UNITED STATES PATENT OFFICE

SAMUEL STEINMETZ, OF KISPEST, HUNGARY

DOORMAT

Application filed June 30, 1928, Serial No. 289,577, and in Hungary October 15, 1927.

This invention relates to improvements in mats, and has for its object to provide a mat of the type ordinarily located at a doorway including a grating provided with cleaning elements and a dirt collector thereunder, the grating being inserted in a grid-like underframe and capable of being lifted out of the latter to facilitate cleaning of all parts of the mat.

10 A further object of the invention is the provision of a mat of the above stated character which may be compactly folded when desired.

In the accompanying drawing wherein an 15 approved embodiment of the invention is illustrated

Fig. 1 is a fragmentary perspective view, with parts removed, of the grating or frame structure provided with cleaning elements;

20 Fig. 2 is a similar view of the grid-like underframe;

Fig. 3 is a fragmentary perspective view, with parts broken away, showing the two separable parts of the mat assembled;

25 Fig. 4 is a detail view in top plan of a part of a modified form of mat;

Fig. 5 is a detail section on the line 5—5 of Fig. 4;

30 Fig. 6 is a fragmentary section similar to Fig. 5 showing further modification of the invention.

Referring to the drawing in detail and more particularly to Figs. 1-3 thereof, the grating A provided with the cleaning elements g and the grid-like underframe B are constructed in such manner that the two parts may be rolled up separately or together as, for instance, when storing or transporting or when removing the mat from the dirt cleaner (not shown) during the operation of cleaning the mat.

The grating or frame-like part A of the mat is composed of flexible strips t of leather, rubber or equivalent material to which pairs 45 of brush bars e₁ and e₂ are secured by retaining members 1 into which the extremities of the brush bars are removably inserted. Brushes g are suitably attached to the bars e₁ and e₂ and the latter with the brushes g 50 may be conveniently and compactly folded

with the flexible strips t as a unit or in conjunction with the other part B of the mat.

The part B is composed of flexible strips t' similar to the strips t and to which are secured pairs of bars b, the bars of each pair being arranged to accommodate in the space c₁ therebetween, a pair of brush bars e₁ and e₂ and the bars b of the respective pairs being spaced apart as indicated at c₂, thus providing an open skeleton-like underframe.

Although it is preferable for convenience in rolling the mat to form the strips t and t' of flexible material, it will be understood that these parts may be replaced by rigid frame members.

In the form of the invention illustrated in Figs. 4 and 5 the retaining members 1' for the brush bars e₁ and e₂ are secured to strips t and provided with recesses in their upper portions of the same shape and accommodating the dove-tailed extremities e₃ of said bars, the latter being retained in position in said recesses by longitudinally displaceable cover plates 1'' confined in position by clips or loops q suitably secured to the members 1'. By removing the cover plates 1'' the brush bars e₁ and e₂ may be removed or interchanged as desired.

In the form of the invention shown in Fig. 6 the retaining members 1' recessed as in Figs. 4 and 5 are provided with hinged cover plates 1''' by which the brush bars are held in position.

The spaces c₁ and c₂ between the bars b of the underframe B and the brush bars e₁ and e₂ permit the mat to be conveniently rolled as a unit when so desired, the bars b being slightly less in length than the distance between the retaining members 1 for the brush bars. It is also desirable to secure cushioning elements e₄ between the brush bars e₁ and e₂ of each pair to maintain these latter in spaced relation to prevent the collection of dirt upon the bars. As the brush bars are fastened only at both ends they are subject to deformation when pressure is applied thereto as when treading upon the mat, the extent of deformation possible being suggested in Fig. 3 where one of the brush bars indicated by the vertical arrows is shown

in a lower position than its companion bar. When treading on the mat the deformation or bending of the brush bars relatively to the bars *b* of the underframe disposes the bristles *g* below the plane of the bar *b* thereby protecting the bristles against mutilation and causing the bristles to be cleaned.

What I claim is:

1. A mat comprising an under frame including a plurality of spaced bars and flexible means connecting the ends of the bars, and an upper frame including a plurality of spaced parallel cleaning elements and flexible means connecting the cleaning elements, said cleaning elements being removably positioned between the bars.

2. A mat comprising an under frame including a plurality of spaced parallel bars, means connecting said bars, an upper frame, placed on the under frame and adapted to be lifted therefrom, said upper frame including a plurality of spaced parallel cleaner bars arranged in pairs and carrying bristles, means connecting the ends of said cleaner bars, each of said pairs of cleaner bars being arranged between two adjacent bars of the under frame, and means for maintaining the cleaner bars in spaced relation.

3. A mat comprising an under frame including a plurality of spaced parallel bars and means connecting said bars, an upper frame placed on the under frame and adapted to be lifted therefrom, said upper frame including a plurality of spaced parallel cleaner elements fitted between the bars of the under frame, flexible strips connecting the ends of the cleaner elements, and carrier members on said strips detachably receiving the ends of the cleaner elements.

20 In testimony whereof I have signed my name to this specification.

SAMUEL STEINMETZ.
